(57) **CLAIM**

The ornamental design for a push up device, as shown and described.

DESCRIPTION

FIG. 1 is a perspective view of a push up device showing the new design;

FIG. 2 is a front view of the push up device shown in FIG. 1;

FIG. 3 is a rear view of the push up device shown in FIG. 1;

FIG. 4 is a side view of the push up device shown in FIG. 1;

FIG. 5 is a side view of the push up device shown in FIG. 1;

FIG. 6 is a bottom view of the push up device shown in FIG. 1; and,

FIG. 7 is a top view of the push up device shown in FIG. 1. In the drawings, the broken lines are for the purpose of illustrating portions of the push up device and form no part of the claimed design.

1 Claim, 7 Drawing Sheets
